WILLIAM B. RUNYAN, OF DAYTON, OHIO, ASSIGNOR TO THE DAYTON MALLEABLE IRON COMPANY, OF DAYTON, OHIO, A CORPORATION OF OHIO.

JACK

Application filed July 18, 1925. Serial No. 44,517.

This invention relates to lifting jacks, and particularly to jacks of the multiple-lift type.

One of the principle objects of the invention is to provide an improved form of lifting jack, which is simple in construction and effective in operation.

Another object of the invention is to provide a jack of the multiple-lift type, so constructed and arranged that the lifting members may be raised into engagement with the load through the normal remote operation of its operating mechanism.

Other objects and advantages will be apparent from the following description when taken in connection with the accompanying drawings, in which:

Fig. 1 is a vertical sectional view through a jack constructed in accordance with the present invention;

Fig. 2 is a fragmentary vertical sectional view through the jack standard, showing details of construction; and

Fig. 3 is a cross sectional view taken on the line 3—3 of Fig. 1, parts being shown in plan.

As illustrating a preferred embodiment, the invention is shown as incorporated in a double screw jack particularly adapted for use in connection with vehicles equipped with balloon tires, which require an extra lift; although it will be understood that the invention may be incorporated in other embodiments and is not necessarily limited to lifting jacks of the screw type.

Referring to the drawing, the jack comprises a hollow standard 10 having a base 11. Loosely mounted within this standard is a hollow or sleeve-like lifting member 12, provided with a cylindrical bore or passage 13. This lifting member or outer screw member 12, which may be referred to as the main lifting member, is externally threaded, as indicated by the numeral 14, and is received within a rotatable collar or nut 15, which is internally threaded, as indicated by the numeral 16, to engage with the threads 14 of the main lifting member. The collar 15 is rotatably supported by the standard 10, preferably upon the upper end thereof, and suitable ball bearings or other anti-friction

means 17 are preferably interposed between the lower end of the collar 15 and the upper end of the standard 10, to insure relatively easy rotation of the collar 15 with respect to the standard. The standard is provided adjacent its upper end with a yoke 20, having an opening 21 therein, through which the main lifting member 12 may readily move, the yoke being provided with a down-turned flange 22 adjacent the opening 21 for cooperation with the upper end of the collar 15 to restrain upward movement thereof, thus maintaining the collar in operative position upon the standard 10. The yoke is also provided with a flanged opening or passage 25, within which is rotatably mounted the socket member 26, having a socket 27 therein, adapted to receive the correspondingly shaped end of an operating handle, not shown. A retaining ring 28 is provided for holding the socket member within the passage 25 in such wise as to permit free rotary motion thereof but to prevent axial motion. The socket member 26 carries upon the inner end thereof a beveled pinion 30, which meshes with a correspondingly beveled gear 31, carried by the collar 15; this arrangement being such that upon rotating the socket member 26, through the medium of a suitable operating handle, the gear 31 will be actuated to cause rotation, in one direction or the other, of the collar 15.

Adjacent the upper end of the bore 13 the inner wall of the main lifting member 12 is provided with internal screw threads, as shown by the numeral 35. Threadedly received within the bore of the main lifting member 12 is a secondary lifting or screw member 36, provided on its exterior with screw threads adapted to cooperate with the internal screw threads 35 of the main lifting member 12, so that upon relative rotation of the main lifting member 12 with respect to the secondary lifting member 36, the secondary lifting member will be removed axially either up or down, relative to the main lifting member 12. The secondary lifting member is provided upon its upper end with a saddle or cap 37, which is adapted to receive the load, such as the axle of an automobile, this cap being preferably rigidly secured to

the secondary lifting member 36, by means of a fastening pin or otherwise.

This construction, as thus far described, is such that upon rotation of the collar 15 relative to the main lifting member 12, the latter is caused to move either up or down within the collar 15. Likewise, rotation of the main lifting member 12 relative to the secondary lifting member 36 will cause movement either up or down of the secondary lifting member 36 within the main lifting member 12. Consequently, should the socket member 26 and collar 15 be rotated while the cap 37 is in engagement with a load, such as for example, the axle of an automobile, then there will be either a rotation of the collar 15 with respect to the main lifting member 12 to cause axial movement of the latter, or the main lifting member 12 may 20 rotate with the collar 15 to cause axial movement of the supplemental lifting member 36 within the main lifting member 12. However, the jack must ordinarily be operated somewhat before it is positioned to bring 25 the cap into contact with the load, and the present invention contemplates in addition to the above described mechanism, yielding means for resisting rotational movement of the main lifting member 12 relative to the 30 standard 10, whereby to insure axial movement of the main lifting member 12 within the collar 15 during initial operation of the jack.

Preferably, this yielding means comprises 35 two spring pressed plungers 50, mounted within a transverse passage 51 in the lower end of the main lifting member 12, a spring 52 being interposed between the plungers to urge them outwardly into contact with the 40 inner wall of the standard 10. The inner wall of the standard, while of generally cylindrical form is provided with surface irregularities which cooperate with the spring pressed plungers 50 in such a way as to introduce a limited impedance tending to 45 resist rotation of the main lifting member 12 within the standard. The surface irregularities on the inner wall of the standard are preferably in the form of longitudinally extending ribs 53 projecting inwardly from the inner wall of the standard. The ribs 53 are of such height and of such shape that when engaged by the spring pressed plungers 50 they offer yielding resistance to the 50 rotation of the main lifting member 12 within the standard; but when the rotational force upon the lifting member 12 is increased sufficiently, then the spring pressed plungers may ride over the ribs 53 thus permitting 55 rotation of the main lifting member 12 within the standard. Any desired number of ribs or corrugations may be provided but there should be three or more to provide means for guiding and for the lateral support of the main lifting member 12 within

the standard. As shown in the drawing four ribs are used, which number gives very satisfactory operating results.

In extending the jack from its fully retracted position, and assuming that the jack is without load upon the cap 37, the jack may be extended to bring the cap 37 into engagement with load by rotating the socket member 26, which in turn rotates the collar 15 about the main lifting member 12, the latter being yieldingly held against rotation within the standard 10 due to the engagement between the spring pressed plungers 50 and the ribs 53. The resistance between the ribs 53 and spring pressed plungers 50 is such as to prevent rotation of the main lifting member 12 under the condition just described. After the cap contacts with the load the inner screw 36 is then held against rotation. By suitably controlling the impeding action of the plungers 50 and corrugations 53, with respect to the friction between the several cooperating threads—any desired subsequent action may be secured. With substantially the proportions shown in the drawing it is found that under load the collar and outer sleeve 12 will rotate together, after the load is picked up, until the member 36 is fully extended; after which the sleeve 12 and member 36 will lock together because of the pin or abutment 54 and will move together axially of the collar. But by properly proportioning the parts full extension of the sleeve 12 may be secured before extension of the inner lifting member 36 results. But in any event the imposition of this limited impedance causes extension of the outer lifting member when there is no load. This limited resistance, which may be for convenience termed an impositive locking means, holds the outer sleeve against rotation relative to the standard so that the collar rotates with respect thereto unless the friction between the threads of the collar and the cooperating threads of the main lifting member is sufficient to cause the plungers to ride over the ribs against the resistance of the spring 52. When the sleeve 12 is held against rotation while the collar is rotating this sleeve, and also the sleeve 36, move axially with respect to the collar and standard, the plungers moving along the ribs or corrugations 53.

The abutment at the lower end of the inner member 36 is preferably the pin 54 which may be inserted in place through a suitable opening 56 in the lower end of the screw 12. This pin strikes against the shoulder 55, at the upper end of the outer screw, when the inner screw is fully extended.

The plungers 50 act as stops, when they contact with the shoulder 57, to limit upward movement of the outer screw member, to thus prevent disassembling of the jack.

When it is desired to retract or lower the

jack, the socket member 26 and collar 15 are rotated in a reverse direction, and the parts are retracted.

In assembling the device, the main lifting member 12 with the secondary lifting member 36 threaded therein, is passed upwardly through the standard from the bottom, through the ball bearing 17, and the threaded collar 15, the socket member 26 having been previously mounted within the passage 25. In order to permit ready insertion of the socket member 26, the standard is cut away at one side, as indicated by the numeral 64, to provide the necessary clearance. The main lifting member 12 having been threaded 15 through the collar 15, a pin 66 is mounted in the upper end of the member 12 to serve as a stop to prevent the member 12 from becoming disengaged from the collar 15 during its downward or retractive movement.

While the form of apparatus herein described constitutes a preferred embodiment of the invention, it is to be understood that the invention is not limited to this precise form 25 of apparatus, and that changes may be made therein without departing from the scope of the invention which is defined in the appended claims.

What is claimed is:

30 1. A lifting jack comprising a hollow standard, main and secondary lifting members disposed in said hollow standard, and means adapted to be actuated to automatically effect successive axial movements of said lifting members, said means comprising not less than three longitudinally extending ribs carried by the hollow standard for guiding the movement of the main elevating member, and impositive control means interposed between the main lifting member and constituting a limited impedance cooperating with said ribs to cause axial movement of the main elevating member during extension and retraction thereof.

45 2. A lifting jack comprising a hollow standard, an internally threaded collar rotatably mounted in the standard, a sleeve lifting member externally threaded to engage with the thread in the collar and internally threaded 50 to engage a secondary lifting member, a secondary lifting member externally threaded to cooperate with the sleeve member, means for rotating the collar, and means tending to prevent rotation of the sleeve, said means comprising longitudinally extending ribs carried 55 by the hollow standard adapted to guide the movements of the sleeve member, and yielding means carried by the sleeve yieldingly engaging said ribs during extension and retraction of said sleeve member.

60 3. A lifting jack comprising a hollow standard, an internally threaded collar rotatably mounted in the standard, a sleeve lifting member externally threaded to engage with the 65 thread in the collar and internally threaded

ed to engage a secondary lifting member, a secondary lifting member externally threaded to cooperate with the sleeve member, means for rotating the collar, and impositive locking means carried by said sleeve and 70 said standard and interposed therebetween tending to prevent rotation of the sleeve, said yielding means constituting a limited impedance comprising a longitudinal surface irregularity formed on one of said parts and a 75 spring pressed plunger carried by the other of said parts and adapted to cooperate with said surface irregularity throughout retraction and elevation of said sleeve.

4. A lifting jack comprising a standard, 80 outer and inner nesting screw lifting members mounted in the standard for extension and retraction, a threaded operating member for the screw lifting members rotatably carried by the standard and in screw threaded operating engagement with the outer of said screw lifting members, means for rotating said operating member, and yielding control means interposed directly between the said standard and outer screw member for yieldingly resisting 85 rotation of the said outer screw member during the extension and retraction thereof.

5. A lifting jack comprising a hollow standard, a threaded operating member rotatably mounted in the standard, a threaded sleeve lifting member, said sleeve lifting member being threaded to engage with the threaded operating member and also to engage a secondary threaded lifting member, a secondary threaded lifting member threaded 95 to cooperatively engage with the sleeve lifting member, means for rotating the operating member, and yielding control means interposed between the said standard and outer screw member for yieldingly resisting rotation of the sleeve lifting member during rotation of the operating member, said yielding control means comprising a spring pressed member carried by said sleeve lifting member and engaging with the said standard to provide a limited impedance to rotation of the said sleeve lifting member.

100 6. A lifting jack comprising a hollow standard, main and secondary lifting members disposed in said hollow standard and each of the said members constructed for rotational movement with respect to the standard, means, independent of the load on the jack for effecting extension of the jack, said means comprising a threaded member in engagement 115 with the main lifting member and impositive locking means interposed between the main lifting member and the standard constituting a limited impedance and means for preventing disengagement of said threaded and said 120 main lifting members during extension of the jack.

In testimony whereof I hereto affix my signature.
